ANGLED ATTACHMENT FOR AN ELECTRIC DRILL OR THE LIKE

Thomas B. Keesling, 17480 Shelburne Way, Los Gatos, Calif., assignor of one-half to C. H. Keesling, San Jose, Calif.

Filed Jan. 2, 1959, Ser. No. 54,027

Term of patent 14 years

(Cl. D54—14)

FIG. 1

FIG. 2

FIG. 3

FIG. 4

FIG. 1 is a perspective view of an angled attachment for an electric drill or the like;

FIG. 2 is a side elevation thereof, the opposite side being a mirror image of this disclosed side;

FIG. 3 is an elevation thereof taken from the right of FIG. 2; and

FIG. 4 is a bottom plan view of the angled attachment.

The dominant features of the design reside in the portion shown in full lines.

I claim:

The ornamental design for an angled attachment for an electric drill or the like, as shown and described.
